Filed Oct. 27, 1967, Ser. No. 9,186

Term of patent 7 years

(Cl. D57—1)

The figure is a view in perspective of a sunglass frame embodying my new design.

The side not shown has substantially the same appearance as the side shown.

The dominant features of my design reside in the portions shown in full lines on the drawing.

I claim:

The ornamental design for a sunglass frame or the like, as shown and described.
